UNITED STATES PATENT OFFICE.

JOSEPH M. BARRETT, OF FOSTORIA, OHIO, ASSIGNOR TO THE "S-C" REGULATOR MANUFACTURING COMPANY, OF FOSTORIA, OHIO, A CORPORATION OF OHIO.

PRESSURE GENERATOR FOR REGULATING DEVICES.

Application filed February 27, 1922. Serial No. 539,789.

This invention relates to a device for producing a variable fluid pressure dependent upon temperature conditions within a container to which the device is connected. For 5 instance this pressure generator may be connected with the water and steam space of a container and produce a variable pressure according to the water level. Such variable pressure may be used for various purposes, 10 as regulating water feed, giving an alarm, closing valves, etc. This invention is concerned with the construction of the generator independently of the particular use thereof. 15 One of the uses for my generator is controlling of the feeding of water to a steam boiler, wherein the difference in temperature between the water and steam in the boiler is used for actuating the control mechanism. Such a regulator system is shown 20 and described in Patent No. 1,193,125, issued August 1, 1916, to N. G. Copley, wherein the pressure within the generator chamber actuates a diaphragm which in turn actuates 25 the valve controlling the feed water.

One of the objects of this invention is the provision of a device which may be satisfactorily employed for various controlling operations and which may be cheaply constructed and readily assembled so as to be 30 sufficiently sensitive to respond quickly to temperature changes.

My invention also contemplates the provision of a device which may be used as a 35 generator in the manner referred to in the above patent but is so constructed that the material of which the generator is formed is not required to withstand boiler pressure. In this connection, my invention is directed 40 toward a construction for eliminating the use of intricate castings.

In carrying out the above objects, I provide a generator wherein a pipe of standard material may be connected at two points to 45 a fluid container, and wherein the generator proper comprises a pressure chamber formed of two castings with a tubular member extending therebetween and entirely surrounding the pipe. The castings are adapted to 50 be rigidly secured to the pipe so as to provide a pressure chamber uncommunicatingly surrounding the pipe, which pressure chamber may be connected through a pressure conduit to a diaphragm-operated valve. In 55 addition, I provide heat radiating vanes

which are separate integral units, and are well adapted for producing variations in heat-radiating capacity, in that the number of vanes associated with each generator may be varied at will.

The means for accomplishing the above objects will be more fully set forth in the following description which relates to the drawing and the essential characteristics of my invention will be summarized in the 65 claim.

In the drawing Fig. 1 is an elevation, partly in section of a generator embodying features of my invention; Figs. 2 and 3 are sectional views on an enlarged scale and 70 showing the method of securing the heads to the casing; Fig. 4 is an elevation showing a suitable connection of the generator to the water column of the boiler; and Fig. 5 is a front elevation of one of the radiating vanes 75 removed from the generator.

In Fig. 4, I have shown a diagrammatic installation embodying inclined conduits 10 and 11 which are connected to a water column 12 above and below respectively, of the 80 normal water level in the boiler and I have shown an oppositely inclined conduit 13 which may be swivelled at 14 and 15 to the conduits 10 and 11 respectively. This conduit 13 is preferably a single length of pipe, 85 the middle of which is approximately on a horizontal plane with the normal water level in the boiler. Surrounding the pipe 13, I have shown a generator indicated as a unit at 16 and provided with a pressure conduit 90 17 which is adapted to be connected to the diaphragm operated valve (not shown).

The construction of the generator as embodied in this invention comprises two heads 20 and 21 which may be rigidly secured, as 95 by brazing, to the pipe 13, and which are adapted to be connected together so as to form an enclosed chamber by the casing 22. The upper head 20 may be threaded to receive a plug 23, while the lower head 21 may 100 be provided with an extension piece 24 which is externally threaded to receive the conduit 17.

Each of the heads is preferably a cup-shaped casting having portions thereof reduced in diameter and externally threaded, as at 30 and 31 respectively. The shoulder formed by the reduced portion with the body of each head comprises an annular inwardly extending V-shaped recess, as at 32, and 33, 110

respectively into which recesses the ends of the casing are adapted to extend. The lower head 21 is provided with a loop as at 35 which may constitute an expansion loop so as to prevent the variations in pressure within the generator from moving the heads longitudinally of the pipe 13.

The casing 22 may be constructed of a single length of light tubular metal having the ends internally threaded, to engage the threaded portions 30 and 31, and having the extreme ends beveled to enter the recesses 32 and 33 respectively. The angle at which the ends of the casing is beveled with reference to the axis of the generator is slightly larger than the angle at which the portions 32 and 33 are recessed. I have found that highly satisfactory results may be obtained by making this difference in angularity approximately 2° . In this way, the ends of the casing may be wedged into the heads whereby a pressure tight joint is more readily secured.

In Figs. 1 to 3, the external diameter of the casing is shown as forming a continuation of the cylindrical portions of the respective heads. This enables the heat radiating vanes to be slipped over the head 20 and to be moved longitudinally of the casing to any desired extent.

Each heat radiating unit comprises an annular radial vane 40 having a laterally extending hub flange 41 which is adapted to closely embrace the exterior of the casing and to be held in frictional engagement therewith. These units may then be positioned as close together as the sensitiveness of the generator requires; it being of course obvious that the greater the number of vanes, the more readily will be the capacity for conducting heat from the generator. In this way, the individual units may be formed separately from the casing and the heads, so that any defect in any one casting will not require the loss of the entire generator.

By constructing the generator after the manner described, it will be seen that the necessity for constructing the casing and heads of material sufficient to withstand boiler pressure is obviated. Thus, the diffi-

culty of securing a casting sufficient to withstand high pressure is overcome. Instead, the heads constitute simple castings, while the casing comprises a single tube which is threaded to engage the heads. Furthermore, the heat radiating vanes are easily adapted for engagement with the tubing and for variations in spacing if such be desired for purposes of securing greater conductivity at one point, than is secured at another.

Since pressure within the generator need be sufficient only to actuate a diaphragm against the force of a spring, it follows that the strength of the parts of the casing is independent of the pressure within the container to which the central tube is connected, and accordingly such casing parts may be quite light and still sufficient for enabling the generator to operate in conjunction with any suitable pressure fluid container. This is advantageous in that a multiplicity of patterns for generators operating on different external pressures is replaced by a single pattern for the heads. The various sizes may then be obtained by merely varying the length of the casing to secure different capacity.

Having thus described my invention, I claim:

A device of the character described having in combination a length of pipe, a pair of cup-shaped heads closely embracing the pipe and facing each other, each of said heads having an externally threaded reduced portion, a cylindrical casing internally threaded at the ends thereof and adapted to engage the threaded portion of the heads, an annular flange at the base of said external threads, said annular flange being cut to provide an annular longitudinally opening V-shaped recess and a complementary V-shaped edge at the end of said cylinder adapted to fit into said recess, the angle of said V-shaped head being slightly greater than the angle of said V-shaped recess.

In testimony whereof, I hereunto affix my signature.

J. M. BARRETT.
